UNITED STATES PATENT OFFICE

ELMER M. DOAN, OF SAN DIEGO, CALIFORNIA

STUD EXTRACTOR

Application filed March 17, 1930. Serial No. 436,595.

This invention relates broadly to extracting tools, and has more particular reference to an extracting tool especially adapted for extracting stud bolts.

5 The primary object of the present invention is to provide a tool of this character which is comparatively simple in construction, thoroughly reliable, practical and efficient in operation, and whereby the use of 10 which the removal or extraction of a stud bolt may be effected without the crossing or mutilation of the thread of the stud bolts.

Other objects and advantages of the invention will become apparent during a study 15 of the following, taken in connection with the accompanying drawings wherein:

Figure 1 is a view partly in section and partly in elevation of one form of my improved stud bolt extractor,

20 Figure 2 is a front elevational view of the stud gripping member forming part of the present invention,

Figure 3 is a perspective view of the body member forming part of the invention,

25 Figure 4 is a horizontal transverse sectional view taken substantially on the line 4-4 of Figure 1,

Figure 5 is a view similar to Figure 1 of a modified form of the invention,

30 Figure 6 is an elevational view of the body member and nut forming parts of the said modification,

Figure 7 is a transverse horizontal sectional view taken substantially on the line 35 7-7 of Figure 5.

Referring more in particular to Figures 1 to 4 inclusive, it will be seen that one form 40 of my invention comprises a shank member 5 having an upper externally threaded head 6. The lower end portion of the shank 5 is

split longitudinally as at 7 to provide a pair 45 of cooperating jaws 8-8. The outer surfaces of the jaws 8 are designated by the reference character 9, and it will be noted that the outer surfaces of these jaws are substantially semi-conical.

At their lower ends, the jaws 8 are provided with an axial bore internally screw threaded as at 10, the threads 10 corresponding 50 to the threads 11 of the stud bolt 12, which

stud bolt 12 has one end threadedly engaging a stud receiving plate 13.

The main body member 14 of the tool includes an upper hexagonal part 15 and a lower conical part 16. The main body member 14 is opened at its opposite end and has a longitudinal bore 16 extending therethrough, and at its lower end, the bore 16 is provided with a conical mouth 17.

The conical or flared mouth 17 as shown to 60 advantage in Figure 1 cooperates with the outer surfaces 9 of the jaws 8, and hence the opening and closing of the jaws 8 will be controlled from the body member 14 in an obvious manner.

In order to prevent relative rotative movement of the body member 14 and shank 5, there is provided within the conical mouth 17 longitudinally extending groove 18 in which slidably seat ribs 19 on the backs of the 70 jaws 8.

When the shanks 5 and main body member 14 are in the position shown in Figure 1, a hexagonal nut 20 is threaded on the end 6 of the shank, and by rotating the nut 20 in the proper direction, it will be seen that the body member 14 will be urged downwardly thus forcing the jaws 8 inwardly into gripping engagement with the stud 11.

The jaws 8 having thus been moved into gripping engagement with the stud 11 by turning the body member 14 through the medium of a wrench or any other suitable implement gripping the upper part 15 of the body member, it is apparent that the stud 11 may be suitably rotated to unscrew the stud 11 thereby effecting the removal thereof from the plate 13.

In that embodiment of the invention shown in Figures 5 to 7 inclusive, it will be seen that I provide a shank member 5' having an upper threaded portion 6', and the lower portion of the shank 6' is split longitudinally as at 7' to provide a pair of coacting jaws 8', which jaws 8' have outer substantially semi-conical surfaces 9', while said jaws 8' are further provided with an axial internal bore having an internal screw threaded 10' corresponding to the thread 11 of the stud 12.

It may be here mentioned, the threads on the upper portion 6' of the shank are left hand threads.

5 The main body member 14' comprises upper hexagonal part 15' and a lower flaring conical part 16'. The upper part 15' is provided with internal left hand threads corresponding to the threads on the upper end portion 6' of the shank 5'.

10 The body member 14' is of course open at its ends, and provided in the upper part 15' is a longitudinal bore internally threaded as before mentioned for threaded engagement with the upper end portion 6' of the shank 5', 70 the bore being designated by the reference character 16', and the lower end or mouth 17' of the bore is made conically flaring for cooperation with the outer surfaces 9' of the jaws 8'.

15 20 In this embodiment of the invention, it will be seen that when the shank 5', and the body member 14' are disposed in that position shown in Figure 5, the shank 5' may be suitably rotated through the medium of a wrench 25 or other suitable tool gripping the squared upper terminal 21 of the shank 5' so that the jaws 8' may be threadedly engaged with the threads of the stud 12.

When the shank 5' has been turned sufficiently for gripping the stud bolt 12, the shank 5' is then held stationary, the wrench still engaging the squared end 21 of the shank, and the main body member 14' may be then rotated in a suitable direction through 35 the medium of a wrench gripping the upper part 15' of the main body member 14 thus urging the same downwardly of the shank 6' resulting as is obvious, in the jaws 8' being moved inwardly toward one another in firm 40 gripping engagement with the stud 12.

45 A block nut 20' is threaded on the upper threaded end 6' of the tank 5, said nut 20' being provided with internal left hand threads for engagement with the threads of said shank and upon rotation thereof it is evident that the nuts will engage the upper end of the body member 14'.

50 The main body member 14' and shank 5' now being in thorough gripping engagement with one another, it is obvious that upon further rotating the main body member 14', the shank 5' will also be rotated thereby effecting a rotation of the stud 12 and consequent removal of the stud.

55 It is thought that from the foregoing description, taken in conjunction with the accompanying drawings, a clear understanding of the operation, utility and advantages of an invention of this character may be had by 60 those skilled in the art without a more detailed description.

Having thus described my invention, what I claim as new is:

65 1. In a stud extractor of the class described, a shank having an upper threaded

portion of uniform diameter, and a lower conical portion, said lower portion being split longitudinally to provide a pair of cooperating gripping jaws having outer semi-conical surfaces, a body member having a bore extending therethrough for accommodating said shank, said body member provided with an upper portion having external wrench gripping faces, and a lower conical portion, the bore of said body member at said lower 70 conical portion provided with a conical mouth for accommodating the conical lower portion of said shank, and a nut threadedly 75 engaging the threaded upper portion of said shank and adapted to engage the upper end 80 of said body member.

2. In a stud extractor of the class described, a shank having an upper threaded portion of uniform diameter, and a lower conical portion, said lower portion being split longitudinally to provide a pair of cooperating gripping jaws having outer semi-conical surfaces, a body member having a bore extending therethrough for accommodating said shank, said body member provided with an upper portion having external wrench gripping faces, and a lower conical portion, the bore of said body member at said lower 85 conical portion provided with a conical mouth for accommodating the conical lower portion of said shank, and a nut threadedly 90 engaging the threaded upper portion of said shank and adapted to engage the upper end 95 of said body member, and said upper portion of said body provided with internal threads for threaded engagement with the 100 threaded portion of said shank.

In testimony whereof I affix my signature.
ELMER M. DOAN.
